UNITED STATES PATENT OFFICE.

HENRY LYMAN BRAYTON, OF OWOSSO, MICHIGAN.

DOOR-OPENING MECHANISM FOR ELEVATORS.

1,405,265.

Specification of Letters Patent. Patented Jan. 31, 1922.

Application filed July 19, 1920. Serial No. 397,372.

To all whom it may concern:

Be it known that I, HENRY L. BRAYTON, a citizen of the United States, and a resident of Owosso, in the county of Shiawassee and 5 State of Michigan, have invented a new and Improved Door-Opening Mechanism for Elevators, of which the following is a full, clear, and exact description.

This invention relates to a mechanism for 10 opening doors in elevator shafts, and has particular reference to one in which the doors may be automatically opened by the movement of the elevator in the shaft.

This invention is related to my United 15 States Patent No. 1,007,428, issued October 31, 1911, entitled Safety gate for elevators.

An object of the invention is to provide a 20 door-opening mechanism which can simply, efficiently, and automatically, be actuated by the elevator operator at will.

Another object resides in the provision of 25 means whereby, when this appliance is used in connection with high-speed elevators, the operating parts are not injured by the shock or contact between the elevator and the operating parts.

A further object resides in the provision 30 of means whereby the doors or gates are more quickly returned to normal.

A still further object resides in the particular arrangement and construction of the 35 parts as hereinafter set forth in the detailed description and claims.

Heretofore, in the provision of automatic 40 means whereby the movement of an elevator in the shaft has been adapted to operate mechanism and to open the doors or gates at different floor levels, either the elevator's movement was so slow as to not cause any great shock or jar on the door-opening 45 mechanism when it came in contact with certain parts of the elevator, or, if the elevator was a high-speed elevator, the shock of this contact speedily put the door-opening mechanism out of order. Moreover, in most instances, gravity alone has been relied upon to return the doors or gates to normal, so that, in the case of high-speed elevators, the elevator would have passed the floor level 50 before the opening had been entirely closed.

My invention is concerned with means whereby these disadvantages are overcome, with particular reference to high-speed elevators, and comprises in general means on 55 an elevator which is adapted to contact with movable door-opening mechanism, which

mechanism is located at the floor level in the shaft in the path of the contacting means above mentioned. The contacting means is provided with certain shiftable parts, which, 60 in their normal position and movement, are adapted to pass by and not contact with the door-operating means above mentioned. When, however, the elevator operator desires to open the door at any particular floor 65 level, by moving the shiftable means from normal position at some instant prior to reaching the desired floor level, this contacting means is so placed that further movement will bring it into contact with the door- 70 opening mechanism, whereby automatic opening of the door is brought about.

My invention further comprises the disposition of resilient means between certain movable parts of the door-opening mechanism and the stationary supports to which they are anchored, whereby the shock of sudden engagement thereof with the contacting mechanism above mentioned will be substantially absorbed by the resilient means. 80

My invention also comprises the disposition of energy-storing devices in connection with the door-opening mechanism so that when the mechanism is operated to open a door energy will be stored in said device 85 and given up to the door-opening mechanism when the door is to be closed, so that the door is more rapidly operated upon closing.

My invention further comprises specific details of construction and arrangement of 90 the parts as will be hereinafter apparent from a consideration of the following description and claims.

The invention is illustrated in the drawings, of which—

Figure 1 represents an elevation of a portion of an elevator shaft opposite a floor level and showing the elevator at that level and the parts in position when the door is open;

Figure 2 is a longitudinal section, with certain parts in elevation, of that portion of the door-opening mechanism which is immediately operated by the elevator;

Figure 3 is a section taken on the line 3—3 105 of Figure 2;

Figure 4 is a section taken on the line 4—4 of Figure 2;

Figure 5 is a partial elevation showing how the ends of the contacting means may 110 be shifted to engage with the door-operating mechanism;

Figure 6 is another view of the same device; and

Figure 7 is an elevation of the door or gate showing the resilient connection between the door or gate and the connection whereby it is operated.

As illustrated in the drawings, the invention is shown as applied to an elevator shaft 1 in which an elevator platform 2 is adapted 10 to move. The platform is provided with the usual upright portions 3 provided with braces 4. To one side of the elevator upright portion 3 adjacent one wall of the shaft 1, there are disposed a pair of arms 5 to which is attached a cam surface 6. At 15 its outer end portions the cam surface 6 is provided with pivoted end portions 7 and 8 which are adapted normally to lie in the position shown in dotted line in Figure 1. 20 A floor level is shown at 9 with the usual elevator shaft opening which may be partially or completely closed by a door or gate 10. This door or gate 10 is connected through the usual system of pulleys by a 25 rope connection 11 with a large pulley 12. This pulley in turn has a smaller pulley 13 thereon which is connected to another rope or flexible connection 14. This flexible connection 14 passes over a pulley 15 which is 30 rigidly fastened to a framework 16 in the side of the elevator shaft adjacent the floor 9, and also over a movable pulley 17 which is mounted on a movable crosshead 18 adapted to move in a slot or guideway 19 in the 35 framework 16. The other end of the flexible connection 14 is fastened to the wall of the shaft by means of a resilient connection 20. As shown in Figure 7, the door or gate is 40 likewise connected to the rope or flexible connection 11 through the medium of a resilient connection or spring 21.

As shown in Figure 2, the crosshead 18 in its movement in the slot 19 eventually is 45 adapted to contact with a slidable plate 22 which is connected to a spring 23 fastened at its other end to the framework 16. The above-mentioned springs or resilient connections are disposed in the operating connections of the door-opening mechanism for 50 the purpose of absorbing any initial shock which may take place when the door-opening mechanism is engaged by the cam surface on the elevator, especially in the case of high-speed elevators.

55 The crosshead 18 is provided with a cam roller 24 which is suitably journaled therein. This cam roller projects from the side of the crosshead 18 and is disposed in such a plane that when the elevator reaches the 60 floor level 9 the cam surface 6 is adapted to contact with the cam roller 24. The pivoted ends 7 and 8 of the cam surface 6 are provided at their inner ends with slotted portions 25 in which a pin on one end of a bell crank lever 26 is adapted to slide. This bell

crank lever 26 is pivoted to the main portion of the cam surface 6, and at its other end 70 27 connects with a resilient connection 28, which may be a spring or may be a rope connection with a small spring disposed intermediate its length. This connection 28 extends to a similar bell crank lever on the other end of the cam surface 6, which in turn makes contact with that pivoted end of the cam surface. It is apparent, therefore, 75 that the action of the resilient connection 28 is such as to normally dispose the pivoted ends of the cam surface 6 in the position shown in dotted lines in Figure 1 and in Figure 5.

In the operation of the device, assuming the doors 10 are lowered and the elevator rising in the shaft 1, it is not always desirable, especially in the case of high-speed elevators, that the door-operating mechanism 80 be actuated as each floor is passed, not only because of the waste of energy involved but also because of the wear and tear on the door-opening mechanism when the doors are needlessly operated. To overcome these 85 defects, therefore, the pivoted ends of the cam surface are provided, so that as the elevator passes any particular floor level the pivoted cam-engaging ends 7 and 8 in their normal position are not in line to contact with the 90 cam roller 24 when it is in its normal retracted position, as represented in Figure 2. Therefore, whenever the operator desires to stop at a certain floor and open the 95 door at this floor level, as he approaches this 100 level he manually moves the desired pivoted end of the cam surface 6 so that this end is momentarily held in the position shown in full line in Figure 1, so that it is adapted to engage with the cam roller 24 which, 105 thereupon, rides on the cam surface 6 and is moved to the position shown in Figure 1, in which position the ropes and flexible connections have been actuated and moved to 110 place the doors in the position shown in Figure 1. As the elevator continues its movement, the cam surface 6 is moved so that the roller 24 passes off the rear portion of the cam surface, whereupon the spring 23 exerts its stored-up energy to force the 115 plate 22 against the crosshead 18 and move the same back to normal position, thus materially assisting the force of gravity in restoring the doors to their closed position.

What I claim is:

1. A door-opening mechanism for elevators, comprising door-opening means disposed in the elevator shaft, a cam surface disposed on the elevator and adapted to engage with the door-opening means during 120 the movement of the elevator, pivoted end portions on said cam surface adapted initially to engage the door-opening mechanism, and resilient means for disposing the ends of the cam surface normally out of the 125 130

line of engagement with the door-opening means.

2. A door-operating mechanism for elevators, comprising a door-operating means disposed within the elevator shaft, a cam surface on the elevator having pivoted ends for initially engaging the door-opening means, a bell crank lever pivoted on the cam surface and connected to said pivoted ends, and a spring connecting the opposite ends of the bell crank levers and adapted to cause the disposal of the pivoted ends of the cam surface normally out of the line of engagement with the door-opening means.
- 10 3. A door-operating mechanism for elevators, comprising a door, operating means for said door located within the elevator shaft,

flexible connections between said operating means and the door, and resilient members disposed in the length of said flexible connections to absorb the initial energy of movement of said connections.

20 4. A door-operating mechanism for elevators, comprising a door, an operating means therefor disposed within the elevator shaft, flexible connections between said operating means and said door, an elevator, means on said elevator to engage the operating mechanism, and spring members disposed at the 25 ends of the flexible connections to absorb the initial energy of contact between the elevator and the operating means.

HENRY LYMAN BRAYTON.
